ATTY'S.

UNITED STATES PATENT OFFICE.

JOHN S. STEVENSON, OF DETROIT, MICHIGAN.

HOPPER-BOTTOM CAR.

No. 809,638.

Specification of Letters Patent.

Patented Jan. 9, 1906.

Application filed April 1, 1905. Serial No. 253,323.

To all whom it may concern:

Be it known that I, JOHN S. STEVENSON, a citizen of the United States, residing at Detroit, Wayne county, Michigan, have invented a certain new and useful Improvement in Hopper-Bottom Cars, of which the following is a full, clear, and exact description, such as will enable others skilled in the art to which it appertains to make and use the same, reference being had to the accompanying drawings, forming part of this specification, in which—

Figure 1 is a side elevational view of a portion of a hopper-bottom car with my improved door-operating mechanism in position thereon. Fig. 2 is a longitudinal sectional view showing the door-operating mechanism. Fig. 3 is a cross-sectional view, and Fig. 4 is a horizontal sectional view on the line 4 4 of Fig. 2.

This invention relates to a new and useful improvement in door-operating mechanism for hopper-bottom cars, the object being to so construct the operating mechanism that the levers which open and close the doors will be positively actuated, guides being provided for confining the path of travel of certain of the pivotal points of said levers, said guides serving also as fixed abutments for taking the weight transmitted through the door onto its operating mechanism.

Another object is to provide means for adjusting the position of the doors with relation to the fixed abutments, whereby the doors may be adjusted to properly seat themselves against the walls of the openings which they are designed to close.

With these objects in view the invention consists in the construction, arrangement, and combination of the several parts, all as will be hereinafter described and afterward pointed out in the claims.

In the drawings, 1 indicates the side wall of the car, from which depend the hopper-sheets 2. It has been usual heretofore to use a continuous plate of metal to form the outside hopper-sheets in order to add strength to the structure; but by my improved method of trussing the doors I am enabled to dispense with the use of material between the hoppers, and thus effect a considerable saving of cost and a reduction in the weight of the car.

3 represents the center sills.

4 is a cross-ridge practically of inverted-V

shape, which extends transversely the car at 55 its central portion and is riveted to the side walls of the car.

5 represents sheets which are provided with vertical flanges riveted together above the center sills, said sheets shedding the load 60 from the center sills and being extended downwardly to form the inside hopper-sheets.

The inclined end floor-sheets of the car are riveted to the side walls, the side hopper-sheets, and the center hopper-sheets 5 by use 65 of integral flanges or connection-angles in a manner well known in the art.

The side walls of the car have depending from them suitable connection-plates 6, which connection-plates support a transversely- 70 disposed I-beam 7. This I-beam, as shown in Fig. 3, has its top flanges riveted to the bottom flanges of the center sills.

8 indicates channels arranged under the I-beam 7, to which said channels are riveted, 75 said channels projecting on each side of the I-beam, as shown in Figs. 1 and 2.

9 represents pressed metal guides channel-shaped in cross-section, (see Fig. 4,) which guides are riveted at their upper ends to the 80 center sill (see Fig. 3) and at their lower ends to the channels 8.

10 is a filler-block riveted between the channels 8 and adjacent the lower ends of the guides 9, said filler-block forming an abut- 85

ment. In addition to forming a support for the transverse I-beam 7 the plates 6 are extended laterally, (see Fig. 1,) so as to provide mounts for the door-operating shafts 11, the outer ends of said shafts being squared for the reception of a wrench or handle, as is well understood. These shafts are provided with locking members 12, as is usual, with which co-operate the pawls 13 in the well-known 95 manner. Shafts 11 extend to the center of the car, finding appropriate bearings in the center sills, and carry at a point between the center sills rock-arms 14. These rock-arms are connected to links 15, said links carrying 100 rollers 16 at their lower ends, which rollers operate in the channels or ways provided by the guides 9. Upon the axles of these rollers are mounted links 17, whose outer ends carry screw-eyes 18.

19 represents the doors, which are hinged to the legs of the central cross-ridge, said doors closing the openings of the hoppers. The

doors in the same transverse plane are connected by a trussed beam 20, said beam having marginal flanges which are riveted to the doors, respectively, the central portion of the beam being embossed or formed with a tapered longitudinally-extending rib, as shown in Figs. 2 and 3. In the space between the doors there is a cap-plate or seat 21, riveted to the marginal flanges of the beam. 22 indicates a pipe arranged between this cap-piece and the embossed rib of the beam, said pipe acting as a spacer and serving to add strength and rigidity to the beam. The screw portion of the screw-eye 18, heretofore referred to, is provided with an adjusting-nut 23, which is designed to impinge against the channel of the beam, the threaded portion of said screw-eye passing through the spacing-pipe 22 and projecting beyond the cap-piece 21, where it receives a nut 24, designed to impinge against said cap-piece.

The door-beam just above described being attached to the free edges of the doors will insure said doors moving in unison, the beam being of such strength as to rigidly connect the doors together, and also prevent the closing edges of the doors from buckling or binding under superposed load. The use of the spacing-pipe and the cap-piece adds to the strength of the beam at its middle portion, where it is not riveted to the doors, and also affords means whereby the rollers 16 may be adjusted with respect to the doors.

The operation of the device will readily be seen by referring to Fig. 2, wherein the door at the left is shown in its open position and the door at the right in its closed position. In the closed position of the doors the rollers 16 are located in the vertical portions of the guides 9, and in addition the link 17 bears upon the abutment-block 10, which takes up the end thrust thereof and relieves the axle of the rollers from transverse strain. In the opening movement of the doors the rock-arm 14 is swung toward and between the guides 9, so that as the links 17 leave the abutment-block the rollers ride freely up the inclined portions of the guides 9 to the position shown at the left in Fig. 2. In closing the doors the arms 14 move in the opposite direction or downwardly, forcing the rollers down the incline and locating the links 17 in line with the abutment-blocks. In the closed position of the door the axis of rotation of arm 14, the pivotal connection between said arm and the link 15, and the pivotal connection between links 15 and 17 are in line. This closed position being a position of dead-center will relieve the shaft 11 of all torsional or twisting strain, and the fact that the end thrust of link 17 against the abutment-block is taken off of the rollers will also reduce the liability of the doors to accidental opening to a minimum. In other words, the

arrangement of the links and guides is such that the doors are effectually locked in their closed position, and practically all strain is taken from the pawls 13.

From the foregoing description it will be noted that the weight of the levers and links materially assists in closing the doors and also in holding the doors closed. The strain from the load on the doors is taken up by the abutment-blocks and channels 8, which are practically under compression at all times, and therefore these strains are substantially neutralized. The ends of channels 8 are supported by the guides 9, and consequently are stiffened against torsional strains. These guides 8 are preferably set at the same angles as the doors, which enables the power to be applied in such manner that the doors can be pulled open with the closing mechanism in case they are frozen, and, furthermore, the doors can be locked open by the same mechanism which is used in closing them. Each door has independent mechanism connected therewith, and consequently less power is required for opening the doors separately than would be the case were they connected to operate in unison from the same source of power.

In this type of double hopper-bottom cars, where the side walls are in the form of plate-girders and the cross-ridge is usually relied upon to support the center sills from the side walls, I prefer not to subject the cross-ridge to this strain in this instance, because said cross-ridge is located above the center sills, and therefore I employ the cross-beam 7, which cross-beam not only serves to support the center sills from the plate-girder sides, but also forms a member to which the parts of the door-operating mechanism may be connected.

I am aware that minor changes in the construction, arrangement, and combination of the several parts of my device can be made and substituted for those herein shown and described without, in the least departing from the nature and principle of my invention.

Having thus described the invention, what is claimed as new, and desired to be secured by Letters Patent, is—

1. In a hopper-bottom car, the combination with plate-girder side walls, a center sill, a central cross-ridge arranged between the plate-girder sides and above the plane of the center sill, and a cross-beam carried by the plate-girder sides in a plane beneath the center sill, for supporting said center sill; substantially as described.

2. In a hopper-bottom car, the combination with hoppers, of a pair of doors closing the openings thereof, a beam having a channel of varying depths, the central part being the deepest, said beam being riveted to the lower edges of said doors, a cap-plate fas-

tened to said beam at the point where the channel is deepest, and a door-operating mechanism connected to said beam between the doors; substantially as described.

5. 3. The combination with a pair of hopper-doors, of a pressed-steel channel-shaped beam riveted to the lower edges thereof, a channel in said beam being of varying depths, the central part being the deepest, a cap-plate between the doors, and a spacer interposed between the cap-plate and the channeled portion of said beam; substantially as described.

4. The combination with a hopper-door, 15 of a channeled beam riveted thereto, a cap-plate riveted to the beam, a pipe in the channel of said beam and in line with said cap-plate, a screw-eye having nuts impinging against the outer faces of said channel and said cap-plate, and a door-operating mechanism connected to said screw-eye; substantially as described.

5. The combination with a hopper-door, 25 of a link pivotally connected thereto, rollers carried by said link, a fixed abutment with which the link co-operates when the door is closed, and guides for said rollers; substantially as described.

6. The combination with hopper-doors, 30 of links pivotally connected thereto, rollers on the inner ends of said links, abutment-blocks against which the links rest when the doors are closed, beams 8 to which said abutment-blocks are riveted, and guides 9 riveted to the ends of said beams, said guides co-operating with said rollers; substantially as described.

7. The combination with center sills, of a cross-beam arranged thereunder, a transverse cross-ridge arranged above the center sills, hopper-doors hinged to the legs of said cross-ridge, longitudinally-disposed beams riveted to the under side of the cross-beam, abutment-blocks and guides on said last- 45 mentioned beams, and links pivotally con-

nected to the hopper-doors and co-operating with said abutment-blocks and guides; substantially as described.

8. The combination with a hopper-door, of a link pivotally connected thereto at one end, the opposite end of said link carrying rollers, and guides for said rollers, which guides have an oblique portion approximately parallel to the plane of the doors in their closed position; substantially as de- 55 scribed.

9. The combination with a hopper-door, 60 of links pivotally connected thereto at one end, said links carrying rollers at their opposite ends, and a guide for said rollers, said guide having substantially vertical portions at its upper and lower extremities, and an intermediate obliquely-disposed portion; substantially as described.

10. The combination with a hopper-door, 65 of an operating mechanism therefor comprising a rock-arm 14, links 15 and 17, rollers 16 at the pivotal connection between said links, channeled members 9 forming guides for said rollers, and an abutment-block; sub- 70 substantially as described.

11. The combination with a hopper-door, 75 of a link pivotally connected thereto at one end, a guide for the opposite end of said link, another link pivotally connected to the guided end of said first-mentioned link, a rock-arm connected to said other link, whereby when the door is in a closed position the rock-arm occupies a position of dead-center, and an abutment-block for supporting the guided end of said first-mentioned link when the door is closed; substantially as described.

In testimony whereof I hereunto affix my signature, in the presence of two witnesses, 85 this 29th day of March, 1905.

JOHN S. STEVENSON.
